UNITED STATES PATENT OFFICE.

CHARLES H. RICH, OF WOOLRICH, PENNSYLVANIA.

SANITARY ATTACHMENT FOR LIP-CONTACTS OF DRINKING VESSELS.

1,076,702.

Specification of Letters Patent.

Patented Oct. 28, 1913.

Application filed September 27, 1912. Serial No. 722,657.

To all whom it may concern:

Be it known that I, CHARLES H. RICH, a citizen of the United States, residing in the city of Woolrich, county of Clinton, State of Pennsylvania, have invented a new and useful Sanitary Attachment for Lip-Contacts of Drinking Vessels, of which the following is a specification.

The object of my invention is to devise 10 a novel fastening device whereby a piece of material of any desired nature may be retained in position with respect to the container with which it is employed so that such piece of material may readily be re- 15 placed, thereby enabling one to maintain the drinking vessel in a sanitary condition at all times.

It further consists of a novel construction 20 of an attachment which may be secured with respect to any desired type of glass, tumbler or other drinking vessel, in order to hold a sanitary piece of paper or other material in a position to prevent the lips of the user coming in contact with the glass or 25 the container which is being used.

It further consists of a novel construction 30 of an attachment which is removably connected with the glass or other container and which engages with the means employed for maintaining the glass or the container in a 35 sanitary condition in such a manner that the lip contacting portion of the glass will be covered by such means.

It further consists of a novel construction 35 of a clip to which is adjustably connected means for securing a piece of material at the upper edge of a container.

It further consists of other novel features 40 of construction, all as will be hereinafter more fully set forth.

For the purpose of illustrating my invention, I have shown in the accompanying drawings preferred embodiments which are at present preferred by me, since the same 45 have been found in practice to give satisfactory and reliable results, although it is to be understood that the various instrumentalities of which my invention consists can be variously arranged and organized and 50 that my invention is not limited to the precise arrangement and organization of these instrumentalities as herein shown and described.

Figure 1 represents a perspective view of 55 a drinking vessel having an attachment embodying my invention in assembled position

with respect thereto. Fig. 2 represents a sectional elevation of a portion of Fig. 1. Fig. 3 represents a sectional elevation of a portion of Fig. 1. Fig. 4 represents a sectional elevation of my novel attachment. Figs. 5, 6 and 7 represent perspective views of other embodiments of my invention. Fig. 8 represents a perspective view of another embodiment of my invention. Fig. 9 represents a perspective view of another embodiment of my invention with a portion of a glass.

Similar numerals of reference indicate corresponding parts in the figures.

Referring to the drawings:—1 designates a container or drinking vessel of any desired or conventional type and which for purposes of illustration I have shown as consisting of an ordinary glass.

Referring first to the embodiments seen in Figs. 1 to 4 inclusive, 2 designates the body portion of my novel attachment to which are preferably secured the arms 3 which latter are formed of resilient or elastic material and have a portion deflected upon itself as is indicated at 4, the strip of material being then bent upon itself in a reverse direction as is indicated at 5, the end of the arm 3 exterior of the body portion 2 is curved or outwardly deflected as is indicated at 6 in order that the attachment may be readily removed from the container 1 when desired. Any desired number of these arms may be employed and in

the present instance I have shown the body portion 2 as provided with two of such arms, which latter may be connected with or separate from the body portion as desired. The body portion 2 is provided at

one end with a tube or sleeve 7 having a slot 8 in the side thereof. Within this tube is mounted a rod 9 having a clasp or grasping portion 10 connected therewith and extending to the slot 8. 11 designates a spring clip which in this embodiment of my invention consists of a single piece of material, the ends of which are connected with the rod 9, it being noted that the spring members of the clip 11 extend downwardly from the upper end of the rod 9, then laterally and then upwardly in order to form a U-shaped portion 12. 13 designates a piece or strip of sanitary material such as for example paper, which is placed over the edge of the container and then the rod 9 is moved downwardly so that the

clip 11 will engage the strip 13 both interiorly and exteriorly of the container, as will be clearly understood by reference to Figs. 1 and 2. When it is desired to place a new piece of sanitary material to cover the lip contacting portion of the container it is simply necessary to move the rod 9 upwardly and remove the piece of unsanitary material 13 which has been used and replace the same with a new piece of sanitary material.

The embodiment seen in Fig. 5 illustrates another form of my invention which may be advantageously employed and readily removed from the container in conjunction with which it is employed. In this embodiment 14 designates a U-shaped body portion, the sides of which are resilient in order that the same may be readily attached to the upper portion of a drinking vessel. This body portion 14 has connected therewith a plate 15 provided with ears 16 in which is pivoted an operating handle 17 to which latter are connected the wires 18 and 19 respectively which are curved or bowed intermediate their ends and their free ends are bent into engagement with each other as indicated at 20. It will be seen in this embodiment of my invention that when the device is in assembled position that in order to remove a piece of unsanitary material, it is simply necessary to actuate the handle 17 to cause the spring arms 18 and 19 to move upwardly out of engagement with the unsanitary piece of material which has already been used.

In the embodiment seen in Fig. 6, the grasping handle consists of a piece of wire 21 which is twisted at 22, and has the free ends 23 and 24 telescoping in the U-shaped clip 25, so that this type of clip may be employed in conjunction with glasses or containers of different dimensions.

In the embodiment seen in Fig. 7, the body portion consists of a knob or handle 26 to which is connected the U-shaped spring clip 27.

It will be seen that in all the embodiments of my invention I employ a U-shaped clip, the sides of which are downwardly deflected in such a manner that the sanitary material employed will be engaged by the lips of the user so that the lips of the user will not come in contact with either the clip itself or the container, and the embodiments seen in Figs. 6 and 7 are specially designed to be carried in the pocket of the user.

The strip of sanitary material is clamped both interiorly of and exteriorly of the drinking vessel so that there is no liability of leakage around such material during the act of drinking.

It will now be seen that my novel device comprises a grasping portion to which is

connected a curved loop-shaped member preferably constructed of spring or resilient material so that the sanitary strip employed will be held in engagement with both the inner and outer walls of the drinking vessel and will smoothly cover the lip-contacting portion of the drinking vessel.

Referring now to the embodiment seen in Fig. 8 I have shown a sanitary piece of material 28 having embedded therein a wire 29 preferably annealed to assist in holding the lip-contact surface of the material to the lip-surface of the drinking vessel. This embodiment may be readily carried in an envelop or in the pocket of the user and readily formed over the edge of a vessel of any size, the wire or other material employed serving to retain the sanitary material in place.

In Fig. 9 I have shown another embodiment of a spring clip in which the inside arc or clip jaw 30 is bent in an arc of greater radius than the outer jaw 31 in order that the clip will readily conform to various sizes of drinking vessels.

It will now be apparent that I have devised a novel and useful construction of a sanitary attachment for lip-contacts of drinking vessels, which embodies the features of advantage enumerated as desirable in the statement of the invention and the above description, and while I have, in the present instance, shown and described preferred embodiments thereof which have been found in practice to give satisfactory and reliable results, it is to be understood that the same are susceptible of modification in various particulars without departing from the spirit or scope of the invention or sacrificing any of its advantages.

Having thus described my invention, what I claim as new and desire to secure by Letters Patent, is:—

1. In a device of the character stated, a body portion, means for securing said body portion in position, a rod movably carried by said body portion, and a loop-shaped clip connected with said rod.

2. In a device of the character stated, a body portion, and a curved loop-shaped clip having its ends connected therewith, one side of said clip being adapted to engage the inner periphery of a vessel and the other side thereof adapted to engage the outer periphery of a vessel.

3. In a device of the character stated, a body portion, means for securing the same in position, a loop-shaped clip having its ends carried by said body portion, one side of said clip being adapted to engage the inner periphery of a vessel and the other side thereof adapted to engage the outer periphery of a vessel, and means for causing relative movement of said clip and body portion.

4. In a device of the character stated, a loop-shaped curved clip of spring material, one side of said clip being adapted to engage the inner periphery of a vessel and the other side thereof adapted to engage the outer periphery of a vessel, and a body portion to which the sides of said loop are fixedly secured, said body portion forming a grasping handle.
- 10 5. In a device of the character stated, a body portion having an aperture therein, a rod movable in said aperture, and a loop-shaped clip connected with said rod.
- 15 6. In a device of the character stated, a body portion, a rod adjustably carried by said body portion, and a loop-shaped clip having its ends connected with said rod and the sides of said loop downwardly curved, whereby one side of the loop will engage
- 20 the inner periphery of a vessel and the other side of said loop the outer periphery of the vessel to clamp a piece of material thereto.
7. In a device of the character stated, a body portion having a sleeve connected therewith and provided with a slot, a rod mounted in said sleeve and provided with a grasping portion extending through said slot, and a loop-shaped clip connected with said rod.
- 25 8. In a device of the character stated, a body portion, a loop-shaped clip having its ends connected with said body portion and having the outer end of the loop adapted to fit over and engage the top of a vessel; the 30 sides of said loop being adapted to engage the inner and outer peripheries of the vessel or sanitary material carried thereby.
